DISPENSER FOR BOTTLED BEVERAGES

Edward B. Sackett, Coulterville, Calif.

Application December 14, 1942, Serial No. 468,902

9 Claims. (Cl. 225—21)

This invention relates in general to a dispenser for bottled beverages, and in particular the invention is directed to, and it is an object to provide, a unique dispenser arranged to support one or more bottles of a beverage, such as beer, and which dispenser is operative to dispense the beverage from the bottles through a conventional draft faucet.

By means of my improved dispenser, a beverage from large size bottles, as for example beer from one-half gallon bottles—which are being used due to war conditions, but which find little favor in the retail trade—cannot be maintained on draft.

A further object of this invention is to provide a beverage dispenser, as in the preceding paragraph, which includes a bottle supporting mechanism or rack which not only supports a plurality of bottles in communication with a beverage dispensing conduit arrangement and sealed against pressure, but also is arranged so that the bottles may be quickly and easily removed when empty and replaced.

A still further object of this invention is to provide a beverage dispenser which includes, in combination, a rack formed to support a beverage bottle in upright position and which rack includes a movable but normally latched platform bar engaged beneath the bottom of the bottle, a seat against which the upper and open end of the neck of the bottle engages in sealing relation whereby to prevent escape of pressure from the bottle, and a draft tube projecting into the bottle through said seat; there being means employed to introduce carbonated gas or air under pressure into the bottle as supported in the rack.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is an elevation of the dispenser as attached to the back of a door of a cabinet.

Figure 2 is an enlarged cross section on line 2—2 of Fig. 1.

Referring now more particularly to the characters of reference on the drawings, the dispenser in the present instance is mounted on the back of a door 1 of a cabinet which includes a front panel 2 through which said door opens, and a top 3.

A horizontal head plate 4 extends across the back of the door in rearwardly projecting relation thereto, said head plate including an attachment flange 5 fixed to the door by any suitable means.

A pair of vertical bottle supporting racks are formed in connection with and extend below the head plate 4, and as each of said racks is a duplicate of the other, a description of one will suffice. 10 Each of the vertical bottle supporting racks comprises opposed vertical side arms 6 spaced apart horizontally a distance only slightly greater than the maximum diameter of the bottle B adapted to be supported in the rack. Vertically spaced rings 15 or circular bands 7 connect the arms 6 to serve as guides for the bottle and to maintain the same centered in the rack. The arms at their upper ends are secured to the head plate 4, while the arms 6 of the respective racks are formed integrally with back plates or flanges 8 which flatly engage and are secured to the back of door 1.

The bottle B is removably secured in each rack in upstanding and consequently non-spilling relation, by means of the following arrangement:

25 Extensible tension link units 9 and 10 respectively depend substantially vertically on opposite sides of each rack, and said tension link units are pivotally connected at their upper ends as at 11 between pairs of ears 12 which are fixed on and depend from the head plate 4; said tension link units being swingable in a plane parallel to the back of door 1. The tension link units 9 and 10 are each fitted at their lower end with a depending clevis, the clevis 13 of the link unit 9 terminating at its lower end only a short distance 30 below the bottom of the rack, whereas the clevis 14 of the link unit 10 terminates at its lower end at a substantially lower point. Both the clevises 13 and 14 open in the direction of swinging movement of the link units, and are adjustably threaded onto the depending stems 15 of said link units so that the effective length of the latter may be altered.

A normally horizontal platform bar 16 is pivoted at one end as at 17, between the legs and at the lower end of clevis 13 for swinging movement in a vertical plane. Intermediate its ends and on top the platform bar 16 is fitted with a compression pad 18 of sponge rubber or the like, 45 and which compression pad is adapted to engage the bottom of the bottle B.

At its free end the platform bar 16 normally projects between the legs of clevis 14 intermediate the ends thereof, and said platform bar is 50 maintained in raised or bottle engaging position

55

by means of a cam 19 pivoted between said legs of clevis 14 at the lower ends thereof for rotative movement into elevating engagement with said platform bar. The cam 19 includes a curved actuating handle 20 which, when the cam is in elevating engagement with the platform bar 16, rests against the bottom of the latter substantially centrally of its ends. As the cam passes dead center in a direction away from the handle, the latter is urged upwardly and thus remains in place until manually lowered and released.

Each of the bottle supporting racks includes a head block 21 having a downwardly flaring bottle neck receiving socket 22 therein; the portion of the block forming the bottom of the socket being a pad P of rubber or the like. When the neck N of the bottle B is forcefully engaged into said socket by the action of platform bar 16, the upper end of said neck engages the bottom of said socket in sealing relation to the atmosphere.

In order to maintain the beverage in the bottles under pressure a conduit 23 is connected to a source of air under pressure or carbonated gas under pressure, by means of a flexible hose 24; the conduit 23 including laterals 25 corresponding to, and which project axially through, the head blocks 21 into the neck N of the corresponding rack-supported bottles.

The draft arrangement of the dispenser comprises depending tubes 26 which extend in clearance relation through the laterals 25 into the bottles from suitable fittings 27 and 28 respectively; the tubes 26 terminating at their lower ends adjacent the bottom of the bottles. A conduit 29 connects the fittings 27 and 28 in parallel; the fitting 28 including a T whose outlet is connected with a flexible hose 30 which leads to and is connected in communication with the inner end of the shank 31 of a draft faucet 32 mounted on and projecting outwardly from the front panel 2 of the cabinet.

Preferably, the hose 30 is attached to a tube 33 of smaller diameter than the bore of the shank of the faucet; said tube leading through said shank to the faucet valve, as indicated. In this manner, only a very small quantity of the beverage is confined in the shank after a dispensing operation, and does not so soon tend to become warm, as would be the case if the shank itself remained filled.

When the bottles B become empty it is only necessary to trip handle 20 downwardly, swing tension link unit 10 laterally sufficiently to permit the escape of platform bar 16, and to lower said bar. The empty bottle then readily escapes from the rack and a full bottle can be substituted; the platform bar 16 being returned to its bottle holding position by proper manipulation of the corresponding cam 19 and handle 20.

The flexible hoses 24 and 30 are of sufficient length to permit the door 1 to be opened for replacement of bottles in the racks.

While I have here shown and described a pair of bottle racks, it is evident that a greater or a lesser number may be employed if desired. Also, while the bottle racks are here shown as being mounted on a hinged door, they may also be mounted on a wall in a "walk-in" box, on the back wall of a cooler, and other places.

From the foregoing description it will be readily seen that I have produced such a device as substantially fulfills the objects of the invention as set forth herein.

While this specification sets forth in detail the present and preferred construction of the device, 75

still in practice such deviations from such detail may be resorted to as do not form a departure from the spirit of the invention, as defined by the appended claims.

Having thus described my invention, what I claim as new and useful and desire to secure by Letters Patent is:

1. A dispenser for bottled beverages comprising a rack adapted to support a bottle in upright position, said rack including at its lower end a movable platform member, said member being movable from a position with the lower end of the rack open to a position supporting a bottle in the rack, means to releasably latch said member in bottle supporting position, means disposed at the upper end of the rack for engagement in sealing relation with the initially open end of the neck of a supported bottle, a draft faucet, and a conduit arrangement in communication between the interior of a supported bottle and said faucet, said conduit arrangement including a tube extending through said sealing means.

2. A dispenser for bottled beverages comprising a rack adapted to support a bottle in upright position, said rack including at its lower end a movable platform member, said member being movable from a position with the lower end of the rack open to a position supporting a bottle in the rack, means to releasably latch said member in bottle supporting position, means disposed at the upper end of the rack for engagement in sealing relation with the initially open end of the neck of a supported bottle, a compression pad secured on said supporting member, said pad being under compression when the member is latched and the bottle neck is in engagement with said sealing means, a draft faucet, and a conduit arrangement in communication between the interior of a supported bottle and said faucet, said conduit arrangement including a tube extending through said sealing means.

3. A dispenser for bottled beverages comprising an upstanding rack adapted to receive an upright bottle from below, a platform bar mounted for movement from a position clear of the lower end of the rack to another position intersecting said end in bottle supporting relation, means carried by said bar adapted to engage the bottom of a bottle in the rack and to urge the bottle upwardly when the bar is in said other position, a sealing element mounted at the upper end of the rack and against which the upper end of the bottle neck seats in sealed relation, and a draft arrangement including a tube projecting into the bottle through said sealing element.

4. A dispenser as in claim 3 in which said bar is swingably mounted in connection with the rack for movement from a depending position to a horizontal position under the bottom of the bottle; said means comprising a compression pad on the top of said bar.

5. A dispenser for bottled beverages comprising a rack adapted to receive an upright bottle from below, tension links depending alongside the rack on opposite sides, a platform bar pivoted at one end to the lower end of one tension link for swinging movement from a depending position to a substantially horizontal position intersecting the lower end of the rack and supporting a bottle therein, means releasably securing said bar adjacent the other end in connection with the lower end portion of the other tension link, a sealing element mounted at the upper end of the rack and against which the upper end of the bottle neck seats in sealed relation.

and a draft arrangement including a tube projecting into the bottle through said sealing element.

6. A dispenser for bottled beverages comprising a rack adapted to receive an upright bottle from below, tension links depending alongside the rack on opposite sides, a platform bar pivoted at one end to the lower end of one tension link for swinging movement from a depending position to a substantially horizontal position intersecting the lower end of the rack and supporting a bottle therein, means releasably securing said bar adjacent the other end in connection with the lower end portion of the other tension link, a sealing element mounted at the upper end of the rack and against which the upper end of the bottle neck seats in sealed relation, and a draft arrangement including a tube projecting into the bottle through said sealing element, there being a compression pad on the bar engaging between said bar and the bottom of the bottle.

7. A dispenser for bottled beverages comprising a rack adapted to receive an upright bottle from below, tension links depending alongside the rack on opposite sides, each tension link including a downwardly opening clevis at its lower end, a platform bar pivoted at one end between the legs of one clevis for swinging movement from

a depending position to another position intersecting the lower end of the rack in bottle supporting relation, a cam pivoted between the legs of the other clevis, the free end of the platform bar, when the latter is in said other position, projecting between the legs of said other clevis and seating on said cam, means to rotate the cam to elevate the platform bar, a sealing element mounted at the upper end of the rack and 10 against which the upper end of the bottle neck seats in sealed relation, and a draft arrangement including a tube projecting into the bottle through said sealing element.

8. A dispenser as in claim 7 in which said tension links are pivotally mounted at their upper ends for swinging movement in a plane parallel to the platform bar.

9. A dispenser as in claim 1 in which said sealing means comprises a head block having a downwardly opening bottle neck receiving socket therein; said socket being of substantial depth and downwardly flaring whereby to readily receive and initially guide the bottle neck to position, the block at the bottom of said socket being of a 20 compressible material which the upper end of the bottle neck engages in sealing relation.

EDWARD B. SACKETT.
